CLAIM

The ornamental design for a case for electronic device, as shown and described.

DESCRIPTION

FIG. 1 is a front perspective view of a case for electronic device showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a rear perspective view thereof;

FIG. 9 is a reference bottom view showing an example state of use wherein a pen is inserted into the case;

FIG. 10 is another reference bottom view showing an example state of use wherein a pen is inserted into the case; and,

FIG. 11 is another reference bottom view showing an example state of use wherein a pen is inserted into the case placed in a standing position.

The broken lines in the figures depict portions of a case for electronic device that form no part of the claimed design.

1 Claim, 8 Drawing Sheets
